Application June 5, 1939, Serial No. 277,539

27 Claims. (Cl. 140—7)

The present invention is concerned with an improved method and means for the production of reticulated wire fabric.

Certain features of the instant application are related to those disclosed in my copending application, Serial No. 234,853, filed October 13, 1938, entitled Hardware and screen cloth machines, and the present application constitutes a continuation in part of said copending application.

In said prior application a method and means are disclosed for making rectangular mesh fabrics with a welded selvage, the weave being of relatively large mesh corresponding to that known in the art as hardware cloth. Although the present invention, broadly speaking, is concerned with the production of any mesh size fabric, it is peculiarly well suited for the manufacture of fabrics of much smaller mesh than those produced by the machine and method of my prior application. Specifically the present invention aims to provide an improved method and machine for the production of welded selvage screening of fine mesh comparable to fly screening, it being understood, however, that the invention is not so limited.

In common with the subject matter of my copending application, the present invention has as one of its aims the elimination of conventional bobbin and shuttle for introduction of the weft wire into interwoven relation with the warp wires and provide in lieu thereof means for introducing an appropriate length of weft wire into the shed of warp wires by transverse feed means in cooperation with a guide associated with the reed of a beater frame, whereby the weft wire is provided in relatively endless amounts. This advantageously permits the machine to operate for long periods of time without interruption and results in a superior product from the standpoint of uniformity of mesh and absence of a multiplicity of undesirable and unsightly joints in the weft wire. Such objectional joints of necessity are present at recurrent intervals in fabric not made by my invention because of the recurrent exhausting and replenishing of the bobbins on the prior art or conventional types of looms.

One object of the present invention is to provide welded selvage fabrics in a continuous manner that will be symmetrically, uniformly and economically produced in a substantially continuous manner and which will be bundled under substantially uniform tension in such form that the inner, outer and intermediate convolutions of the roll are approximately equally tensioned and compressed.

Another object is the provision of improved

feeding means for the weft wires involving the use of novel pulling, pushing and guiding means therefor whereby quite irrespective of the small gage of the wire, positive and accurate feed is effected. It is a further object to provide novel coating machine elements that are rendered effective to interrupt the machine the instant that improper operating conditions occur. Another object is to provide improved selvaging means effective to condition and autogenously unite the selvage ends of the weft wires to components of the fabric continuously without interrupting the advancement thereof during its formation. It is a more specific object to provide simplified yet highly effective electrical means for control and operation of the selvaging means.

Other collateral objects and advantages which are inherent in the method and machine of the present invention will be apparent from consideration of the following detail disclosure and the appended claims, when read in connection with the accompanying drawings.

In the drawings,

Figure 1 represents a right-hand, side-elevational view of a preferred embodiment of the present invention, which is complete in nearly every detail, with the exception of the warp wire supply reels, which are omitted from the right-hand side of the view.

Figure 2 represents a transverse, sectional-elevational view of the machine taken at line II—II, Figure 1, looking in the direction of the arrows.

Figure 3 is an enlarged, fragmentary view taken of the right-hand, side-elevation of the machine showing the selvaging device, the reed and beater frame assembly, including the operating cam for the latter, and the heddles forming the warp shed.

Figure 4 is a transverse, sectional-elevational view taken along the irregular line IV—IV in Figure 3.

Figure 5 is an enlarged, sectional-elevational view taken along line V—V in Figure 4, illustrating a detail.

Figure 6 is a fragmentary plan view, partly sectioned and enlarged, showing the left-hand end of the reed in cooperation with the stationary weft wire guide, and the movement of the former in positioning weft wires into interwoven relation with warp wires.

Figure 7 is an enlarged, front-elevational view of the weft wire feed instrumentalities, as they appear at the left-hand side of the view of Figure 2.

Figure 8 is a sectional view taken at line VIII—VIII in Figure 7.

Figure 9 is a sectional view taken at line IX—IX in Figure 7.

Figure 10 is an enlarged, top-plan view of the left-hand selvaging unit showing the initial welder, the trimmer, the formers, and the final welder.

Figure 11 is a side-elevational view of the selvaging unit disclosed in Figure 10, looking from 10 the fabric (right-hand) side of the latter.

Figure 12 is a sectional view of the selvaging unit taken along line XII—XII of Figure 11, showing the weft trimmer and initial former.

Figure 13 is an enlarged sectional view taken 15 along line XIII—XIII in Figure 11, illustrating the tools of the initial former, and the cooperation therebetween relative to the fabric.

Figure 14 is a further enlargement of that which is shown in Figure 13, and corresponds in 20 view point to the latter.

Figure 15 is a sectional view taken along line XV—XV of Figure 11, showing the final former and final welder.

Figure 16 is a top-plan view of the fabric winding or bundling mechanism, illustrating also the left-hand end of the machine as viewed in Figure 25 1, and showing the cooperation between the bundler and the latter.

Figure 17 is a right-hand, side-elevational view 30 of the winding or bundling mechanism shown in Figure 16.

Figure 18 is a greatly enlarged, fragmentary, top-plan view of the right-hand selvage edge of the fabric, showing its progression as it is 35 trimmed, formed, and welded by the selvaging unit.

Figure 19 is a plan view of a finished web of 40 fabric, drawn approximately to full size for house screening and the like; and

Figure 20 is an enlarged, cross-sectional view of 45 the stationary weft wire guide, sectioned as in Figure 8.

Before referring in detail to the mechanism illustrated in the accompanying drawings, it is to be noted that while not strictly limited thereto, the method and mechanism disclosed is effective to produce screen fabric of the general character shown in Figures 18 and 19. This fabric constitutes a multiplicity of longitudinal components such as line or warp wires L and associated cross wires, herein sometimes referred to as weft or picket wires P. The picket wires are welded or otherwise autogenously integrated at their intersections with the outer marginal line wires, as indicated at A. The outer extremities of the picket wires are cut off in sequence so that they extend laterally a uniform distance from the outermost line wire, the point of cut off being indicated at C in Figure 18. After such cutting, the ends of the picket wires are bent at an angle so as to lie in a plane substantially perpendicular to that of the fabric in a manner hereinafter more fully set forth and as suggested pictorially in Figure 14. Thereafter the thus bent ends of the picket wires are brought into the relationship pictured at the left of Figure 18, wherein it is apparent that the outermost extremity of each picket wire overlaps an oblique portion of its neighboring picket wire. The thus overlapped picket wires are subsequently welded or otherwise autogenously integrated to complete the selvage. Reference will now be made to the general assembly and functional relationships of my improved mechanism for forming the fabric.

General arrangement

As viewed in Figure 1, warp or line wires L are introduced to the machine at the right-hand end of this view from a supply depot (not shown), and are directed, by driven feed rolls 1, through an automatic tensioning device 2, stationary guides 3, and heddles 4, to the reed member 5, through which they pass. At this point weft wires or pickets P are introduced in interwoven relation with the warp wires to form the web of fabric F. From here the fabric continuously advances, and is operated on by right- and left-hand selvaging units 6, which complete the fabric. From thence the fabric F is carried through driven feed rolls 7, and is conducted on to the bundling mechanism 8.

As has already been stated, many of the structural and functional characteristics of the machine illustrated here for purposes of disclosing a preferred embodiment of the present invention, are substantially the same as those shown and described in my copending application, above identified. The means for handling and properly tensioning the warp wires, and for delivering the fabric, together with their associated drives and related controls, are set forth with great particularity in said copending application. It will be sufficient to point out for this application that the warp wires L, proceeding from the stationary guides 3, are passed through the heddles 4, whereby the shed is formed. The reed member 5 is adapted to be oscillated backwards and forwards in the zone of the warp shed, whereby it functions to place pickets into interwoven relation with the warp wires.

The reed, beater frame, and associated parts

The reed of the present invention is, as will be seen by reference to Figures 4 and 6, composed of a plurality of dents 9 formed from flat metal strips that are arranged on end in side-by-side relationship to each other on the beater frame 10 (see also Figure 3). The dents are held in place upon the beater frame by means of a clamp 11, as is fully described in my copending application, and are maintained in spaced relation relative to each other by a plurality of spacer washers 12, by means of which the warp wire slots 13 are formed. The assembly of dents is rendered a unitary structure by tie rods 14, upon which each of the dents is impaled, and made fast by nuts 15.

As in the reed illustrated in my copending application, a notch is provided upon the front edge of each dent at a point intermediate the ends thereof, which notches, when the dents are assembled to form the reed, register in a substantially horizontal line extending transversely of the machine to provide a weft wire guide slot 16 across the face of the reed panel 5.

The guide slot 16 is adapted to receive picket lengths from a continuous supply of weft wire by the means illustrated in Figures 2 and 7, which will be described hereinafter. In order to constrain the travel of the wire to the slot 16, as it is being pushed therethrough, a retractable closure 17 (see Figure 3) is provided therefor, which likewise is similar to that previously disclosed by me in my copending application above identified. This device comprises a slotted member arranged along the face of the reed panel 5, the slots of which are lined with the slots 13 of the reed panel in directions longitudinally of the

machine and in the vertical planes of the warp wires.

Portions of the closure member 17 intermediate the slots therein register with the face of the dents 9 into which the weft wire guide slot 16 is disposed. When the beater frame 10 is moved to its rearmost position by its operating cam 18, the weft wire guide slot 16 in the reed panel 5 falls in coaxial alignment with a stationary weft wire guide 19, illustrated in Figures 2, 4 and 7. When the parts are in this relationship, the instrumentalities illustrated in Figures 3 and 4 for controlling the closure member 17 are in such position as to dispose the latter in overlying relationship relative to the slot 16 substantially to close the same. Thus, when a weft wire is introduced into the slot, it is prevented from falling out of the open side thereof, and is guided across the width of the fabric being formed.

The mechanisms for controlling the closure member 17 are the same as those shown in my copending application, and comprise an oscillating rod 20 which is pivoted by means of links 21 upon the beater frame 10. From the rod 20 extends a plurality of connecting rods 22, upon which the closure member 17 is supported. This assembly is retained against the face of the reed panel 5 by means of clamps 23, best seen in Figure 4, and motion is imparted to the former by a connecting rod 24, which is actuated through a suitable lever 25 by cams 26 (see Figure 2).

When the beater frame cam 18 advances the reed panel to the forward end of its movement, which position may be seen in Figures 1, 3 and 6, the cams 26 are effective to move the connecting rod 24 downwardly so as to retract the associated linkage and connecting rods a sufficient distance to dispose the closure member 17 below the weft wire guide slot 16, which permits the weft wire picket confined therein to be discharged, and to remain in the bite of the warp wires after the heddles have reversed the shed and the beater frame has withdrawn the reed panel therefrom.

As is disclosed in my above mentioned copending application, the beater frame 10 is so operated and controlled by the cam 18 that it holds the reed 5 stationary during the period in which a weft wire is being charged thereinto, after which it moves the reed rapidly forward to position the picket at the point of warp wire convergence in the shed. It is provided that the reed firmly bear upon each picket until the heddles 4 reverse the warp shed to lock the picket in place. However, since the fabric advances continuously without interruption, the cam 18 is designed to move the beater frame and reed forward in a creeping movement during this holding interval so as to keep pace with the fabric until the picket is interwoven.

Weft feed

The feed mechanism for advancing weft wires into the reed panel guide slot 16, last described, is best illustrated in Figures 2, 4 and 7, to which reference is now made.

The weft wire P is supplied in any quantity from a reel 30, from which it is withdrawn by means of a positively driven puller drum 31 through an automatic slack maintaining guide 32. The puller drum 31 delivers the wire upwardly through driven pinch rolls 33-35, into a looping guide 34, from which it is delivered in a horizontal line toward the machine beneath the pinch roll 35, through tensioning rollers 36,

and intermittently acting feed rolls 37. From these latter, lengths of weft wire are recurrently fed through the stationary weft wire guide 19 into the weft wire guide slot 16 in the reed panel 5, as has already been described.

As is disclosed in my prior application, above referred to, the weft wire is arranged to be paid from a driven reel which helps to relieve it of most of its frictional drag. Such a reel is illustrated at 30 in Figure 2. It comprises a standard 38 at the top of which is mounted a radially extending arm 39, which is afforded bearing axially of the standard 38 by a fixed collar 40. At the extremity of the arm 39 is a pivot shaft, upon which the reel, composed of a basket 41 and base 42, is journaled for rotation about an axis that is eccentric with the axis of the standard 38. Cooperating radial lugs 43 on the arm 39 and on the fixed collar 40 are provided with a set screw (not shown) by means of which the arm, and, hence, the reel carried at the other end thereof, may be bodily moved around the axis of the standard 38.

The reel base is fashioned into a belt pulley 42a, which is adapted to accommodate a driving belt 44, through which it is frictionally, though positively, rotated. The driving belt 44 receives its power from a pulley assembly 45, which is positively driven through gearing 46, shafting 47, and a clutch 48, connected to one of the power shafts of the machine proper.

As best appears in Figure 2, it will be seen that the pulley assembly 45 comprises a variable speed pulley of the double-cone variety in which two halves 49a and 49b are mounted for rotation about a vertical stub axle 50, which is rotated through gearing 46, as has already been mentioned. The lower half 49b of the cone pulley is urged toward the upper half by a compression spring 51, so that, normally, the complementary halves of the pulley will be maintained in contiguous relation. When the reel is adjusted as close to the machine as is permissible without sacrificing driving tension on the belt 44, the latter engages the cones of the pulley at their greatest effective diameter, and, hence, the reel will be driven at its greatest speed as a consequence thereof. However, when a slower speed of rotation is desired, the reel standard arm 39 may be turned to remove the reel pulley 42a a short distance from the pulley 45, and this will vary the effective diameter of the latter causing the speed of the revolution of the reel to be reduced. In this way, the rate at which the wire P is paid from the reel is effectively controlled to conform to the requirements of the machine.

From the reel, the wire is led upwardly to the slack-maintaining device 32, which comprises a rectangular support 52 having guide pulleys 53 and 54 at the extremities thereof for leading the wire fairly down to the puller drum 31. Before passing from the pulley 53 to the pulley 54, the wire is looped downwardly in figure-8 configuration, as is shown at 55 in Figure 2, so as to pass around a sheave 57 that is carried upon the free end of a movable arm 56, which arm is pivoted at its other end to the vertical leg of the rectangular frame 52. The figure-8 loop of wire 55, under proper operating conditions, maintains the arm 56 at or near the horizontal, and is aided in this function by a weak compression spring 58, which is arranged yieldingly to resist any movement of the arm above or below such positions. A pair of contacts 59 are carried upon the pivoted arm 56 so as to extend radially there-

from relative to the pivotal axis thereof. Disposed between these two contacts 59 is a co-operating contact 60 mounted stationarily upon the vertical leg of the rectangular frame 52.

The operation of this device is such that, if an excessive amount of wire is drawn from the supply reel 30, as might happen should something interrupt or foul the smooth operation of the machine, the figure-8 loop of slack 55 in the weft wire will grow to the point where the arm 56 is no longer supported thereby, and, hence, the latter is permitted to drop against the yielding resistance of the compression spring 58, until one of the contacts 59 engages the stationary contact 60 to cause, through a relay circuit (not shown) the stoppage of the machine. This permits the operator to correct the trouble that originally caused the excessive slack to form. Conversely, if the machine takes up wire faster than it is paid out by the reel 30, the figure-8 loop 55 of slack wire is shortened sufficiently to lift the arm 56, whereby the other contact 59 is moved into engagement with the stationary contact 60 to stop the operation of the machine. This latter eventuality usually arises when the supply of wire becomes fouled on the reel, or when the reel is being driven at a rate of speed insufficient for the machine's requirements.

The wire P is then passed at least 1½ turns around a puller drum 31, which pulls it from the supply and discharges it upwardly to pinch rolls 33 and 35. These pinch rolls feed the wire into a loop S within the loop guide 34, from whence the wire passes on to the feed rolls 37, which are intermittently opened and closed so as to effect a periodic cessation in the advancement of the wire. The drives for these several instrumentalities may be best understood by reference to Figures 7, 8 and 9.

It will be observed that the gearing 46, mentioned hereinbefore in connection with the drive to the split cone reel pulley, is provided with a sprocket 61, which, through a chain 62, serves to transmit power to an intermediate sprocket 63, that is directly connected to, and drives an adjacent sprocket 64. This latter sprocket accommodates a chain 65, which is led upwardly to a sprocket 66 affixed to the shaft of the pinch roll 33 over which it passes, and, then, downwardly beneath a tensioning pulley 67, wherefrom it extends to drive a sprocket 68 that imparts motion to the lower roll of the intermittent feed rolls 37. The upper feed roll is driven through spur gears 68a coacting between the upper and lower shafts of these rolls. From the sprocket 68 the chain 65 extends downwardly beneath the drive sprocket 64. Thus is continuous motion imparted to all of the sprockets and rolls associated in the drive of the chain 65.

The puller drum 31 receives its power through a gear train 69 acting on the rear ends of the pinch roll and puller drum shafts, as is best seen in Figure 9. This gear train is powered by the chain 65, already described above, and the sprocket 66, which together directly power a spur gear 70, and this, in turn, through an idler gear 71, turns the puller drum gear 72 by which the latter is rotated through shaft 73.

It will be noted that all of the pinch rolls in this arrangement, including the puller drum, are continuously driven, and, as such, fail to provide the necessary condition for the intermittent advancement of the weft wire to the reed panel. It will be understood that the wire may only be advanced, in this connection, when the beater

frame is at the rearmost point of its cycle of movement in which position the reed 5 carried thereon aligns with the stationary weft wire guide 19, so that a picket may be charged into the weft wire guide slot 16. During the movement of the reed panel to its forwardmost position, the advancement of the weft wire must be automatically suspended pending its return.

To effect this, provision is made to feed the prerequisite amount of wire, and, then, to interrupt such feed without requiring that any of the rolls in question be stopped. This is accomplished by the means shown in Figures 7 and 8, by raising and lowering the uppermost of the intermittent feed rolls 37 relative to the lower roll thereof. The wire will only be advanced when the upper roll pushes it against the lower roll and holds it there to effect its movement. The opening and closing of the feed rolls is accomplished by the means illustrated in Figure 8, which comprises a movable bearing 74 in which the upper of the pair of feed rolls 37 is mounted. Intermittent motion is imparted to the bearing 74 through a shaft 75 and a controller arm 76, the lower extremity of which bears upon a cam 77. As this cam raises and lowers the arm 76, the upper feed roll is raised and lowered a corresponding amount to feed the wire at predetermined intervals only. The cam 77 is powered from the prime mover of the machine through the shafting seen in Figure 2.

The arrangements of the several parts is such that the puller drum 31 will continuously advance wire through the bite of the pinch rolls 33 and 35, and, since these latter instrumentalities continuously rotate to effect an uninterrupted advance of the wire, a loop of slack is formed in the loop guide 34, as is indicated at S in Figures 2 and 7, during the period in which the feed rolls 37 are not advancing the wire. Upon resumption of the feed of the wire by the feed rolls 37, a sufficient loop of slack S will have accumulated to satisfy the requirements for the delivery of one picket length of weft wire, which is enough for one operating period of the feed rolls 37, without requiring that these latter draw from the source of wire behind the puller drum 31. It will be appreciated that this is a very simple way in which to facilitate the starting and stopping of the wire without injury or breakage thereof. It is especially important in dealing with fine wires in the order of .010 of an inch in diameter, such as compose the ordinary grades of house screening, that some system be adopted to reduce all drag and inertia to an absolute minimum so as to preclude the wire's being broken when the feed rolls 37 come together. The loop of slack S, which is periodically accumulated in the loop guide 34, provides an ideal solution to this problem.

The loop guide comprises a plate 78 on which is hinged a gate member 79 that may be opened by pivoting outwardly on the pintle hinge 80, and that may be closed and retained closed by a latch 81. The clearance between the elements of the gate 79 and the plate 78 is no more than sufficient to accommodate one diameter of the wire being looped therein without binding or unduly crowding the latter.

The tensioning member 36, through which the wire passes last before entering the intermittent feed rolls 37, is constructed and arranged with a view toward facilitating the threading of the wire through the machine. It comprises an upper bearing block 82 and a lower bearing block

82a in which are journaled rollers for rotation on axes transverse to the long axis of the wire passing therethrough. When in operable position, the lowest peripheral points on the rollers mounted by the upper bearing block 82, and the highest peripheral points on the rollers mounted by the lower bearing block 82a, are, relative to each other, past that point, in favor of propinquity, wherein a common plane would pass tangent to each of the rollers of both bearing blocks. In other words, a serpentine passage is provided through which the wire must pass, and this serves slightly to tension the wire to insure its being fairly led through the feed rolls and associated guides.

To facilitate threading the wire, the roller bearing block 82a is slidably mounted relative to the stationary upper block 82, and is movable into operable position, as well as retractable from the latter, by means of a cam 83 that is actuated by a small hand lever 84. By manipulating the lever 84, the lower bearing block 82a is permitted to drop, thus creating a considerable space between the rollers of the upper bearing block 82 and those of the lower bearing block 82a. This permits the wire to be laid in between these two members, after which the small lever 84 is manipulated to cause the cam 83 to raise the lower bearing block 82a until the wire is forced to assume a serpentine disposition about the peripheries of the rollers.

The matter of guiding the wire to and from the intermittent feed rolls 37 presented a problem of providing a straight guide that would be of sufficiently small internal dimensions to confine the wire closely without permitting it to buckle, and, yet, of sufficient length so as to reach from the intermittent feed roll to the reed panel without deviating from a substantially straight path. Considering that the wire may be in the neighborhood of .010 of an inch in diameter, and that the guide in question is around two feet in length, it will be appreciated that manufacturing difficulties might be encountered in the provision of such a guide.

The guide 19 is designed to solve this problem, and its construction may be understood by reference to Figures 7, 8 and 20. The guide 19 illustrated in Figure 8 is shown in section, but this view is of insufficient size to be very helpful from the standpoint of a clear disclosure; hence, Figure 20 has been provided to give a more accurate representation as well as a clearer idea of what the guide 19 looks like in cross section.

It will be observed that it is composed of a pair of bars of rectangular section, which comprise complementary guide-halves 85 and 85a. Each bar has been relieved from a line running longitudinally down its proximate face to one edge thereof, so that there is a slight stepped portion, or shoulder, 86 provided on each bar. By assembling and arranging these bars as illustrated in Figure 20, it will be seen that an opening substantially square in cross section is afforded down the approximate center of the mass of the assembled blocks. This opening may, in size, be varied by enlarging the height of the shoulders 86, and by moving the blocks relative to each other so as to increase the lateral dimensions of the bore. This permits of a very accurate confining of the wire without binding, and assures that it travels along as nearly a perfectly straight path as it is possible to provide. It has the added advantage of permitting the removal and the assembly of the guide during the time 75

when the wire is in position, since, if the lower element 85a is laid in place with the wire disposed to the left-hand side of its shoulder 86, the upper block may be slid into place from the left-hand side (as viewed in Figure 20) without at any time crushing the wire and without entailing any arduous threading operations. The size of the wire being predetermined, the depth of the shoulders 86 may be machined to proper dimension in the first instance, so that it is only necessary to bring the outer edges of the blocks into flush relationship to provide an internal bore of the size required.

As is disclosed in my copending application, the inner end of this stationary weft wire guide is disposed in contiguous relation to the reed panel so that, as the latter is moved to advance a picket into position, the coaction between the guide and reed is such as to shear the picket length carried by the reed from the weft wire remaining in the guide. As will later appear, trimmers for both ends of the pickets are provided in the selvaging units accurately to align the wire ends.

As is viewed in Figures 7 and 8, the guide 19, described last above, is held in place by suitable brackets 87 to which clamps 88 hold the guide by means of bolts 89.

Earlier in the description of the weft wire feed mechanism, and particularly in the discussion of Figure 2, it was mentioned that the source of power to these instrumentalities was supplied from one of the driven shafts of the machine through a clutch 48. This clutch, which appears in Figures 2 and 8, is of positive variety, and includes a circular disc 90 on the driving shaft, and a retractable T-head 91 on the driven shaft, which head is provided with pins 92 that are adapted for insertion in pairs of diametrically opposite holes 93 formed in the disc 90. This arrangement provides that the T-head on the driven shaft may be withdrawn from engagement with the disc element of the clutch on the driving shaft, and turned relative thereto, until the proper relationship is had to coordinate the weft wire feeding mechanism with the other operating instrumentalities of the machine. It will be noted that the holes in the disc element 90 are sufficiently close together so as to admit of an adjustment within 20 degrees out of a possible 360 degrees relative to the predisposition of the two shafts.

In Figures 3, 4 and 5, there is illustrated a device for stopping the machine in the event an inadequate amount of weft wire is fed through the reed panel groove 16 to provide a picket of the required length. At the end of the reed remote from that at which the weft wire is introduced thereto, there is attached to the beater frame a pair of bearings 180 in which is journaled a shaft 181 that is adapted to be rocked within a short arc of movement by means of a rod 182, a lever 183 having a cam follower 184 extending therefrom, and a cam 185. A compression spring 186 secured between a stationary point on the housing and a point on the lever 183 assures that the cam follower 184 is always in positive engagement with the effective surface of the cam 185. The rod 182 extends through the outer extremity of a lever 187 affixed to the shaft 181. The motion to which the cam 185 subjects the rod 182 is imparted to the shaft 181 through the lever 187 by a compression spring 188 that is disposed about the rod 182 between a stop 189 thereon and the shaft lever 187.

The inner end of the shaft 181 is provided with

an extension 190 which is adapted to lie across the end of the reed panel 5 so as to be oscillated back and forth across the end of the weft wire slot 16 therein. Beneath the shaft 181 is a contactor 191 (see Figures 4 and 5) through which a machine stop relay circuit may be short-circuited should an extension 192 on the shaft come into engagement therewith.

The operation of the device is as follows: The cam 185 is so disposed in its cycle of operation as to raise the extension 190 clear of the end of the panel slot 16 at the time a wire is being advanced therethrough, and to maintain this relationship until the time when the lead end of the weft wire should be projecting from the reed at the panel slot 16. When this condition has been reached, the cam 185 imparts a lifting motion to the rod 182, whereby the shaft 181 is revolved and the extension 190 carried thereby is caused to travel downwardly toward the reed panel slot 16. If the weft wire has been fed through successfully, the extension 190 will bear thereagainst and be restrained from further movement in that direction; the remainder of the movement afforded by the cam, rod, etc., being harmlessly dissipated in the compression spring 188. Should, however, the weft wire fail to feed through the reed panel as it should, the motion of the cam will cause the extension 190 to pass down across the end of the panel groove 16, until the extension 192 of the shaft 181 engages the contactor 191 to short-circuit the machine stop relays (not shown) and instantly stop the machine. This permits the operator to ascertain the reason for the weft wire picket's having failed to reach the end of its intended course of movement through the reed panel, and is a positive safeguard against the placement of pickets too short in length for proper coaction with the selvaging steps that immediately follow.

Selvage formation

After the pickets are interwoven with the warp wires by the various instrumentalities herein described, the fabric F is complete except for the selvaging operation that is carried out by the complementary selvaging units disposed at each side of the machine adjacent the fabric exit end thereof. Since one of these units is exactly the same as the other with the exception of the direction in which it faces, the left-hand unit has been adopted for purposes of illustration to serve for both. In Figures 10-15, inclusive, is illustrated a typical form of selvaging unit which has been generally designated at 6 in Figures 1 and 3.

As is disclosed in my previous application, above referred to, the side frames of the machine are, as is best seen in Figure 2, formed with slide bearings 94 on which is mounted a table 95 that is adapted for reciprocatory movement longitudinally of the machine for reasons to become apparent hereinafter. This table is provided with a bearing groove 96 that extends throughout its length across the machine. This may be seen in Figures 3 and 11.

The units are supported on a base 97 that is mounted within the groove 96 of the table 95, and across which they may be slid into any position relative to each other for accommodating any width of fabric to be acted upon. Suitable clamps 97a are provided to anchor the base 97 at any position across the table 95.

The upper portion of the base 97 is provided with a rack 98 that extends longitudinally of the machine, as may be best seen in Figures 10 and

11. The rack on the fabric side of the base is undercut (see Figures 12 and 13) and on its side remote from the fabric is perpendicular to the plane of the base 97. The selvaging instrumentalities are each provided with a mounting 99 which has an undercut slot extending upwardly from its under-surface for cooperation with the undercut face of the rack 98. The mounting slot is made sufficiently large in lateral dimensions so as to admit of the mountings being laid into position over the undercut rack 98 without tilting, and is adapted to be drawn into position where the undercut portions of the rack and the mounting cooperate to form a tight joint, locking the mounting and associated parts securely in place. This latter is effected by means of bolts 100, which may be seen in Figures 12 and 15, but which also appear in Figure 11.

In order that the mountings may be moved longitudinally of the rack 98 with respect to each other, so that the various instrumentalities for forming the selvages, to be described in full hereinafter, may be brought into proper registration with the picket ends, there is provided in each mounting 99 a pinion 101, which is journaled at each of its ends within the mounting, and which extends across the rack 98 so that the teeth of the pinion are in cooperative engagement with the teeth of the latter. The outer ends of the pinions are extended through the mountings so as to afford purchase for a crank, wrench, or other adjusting tool. They may be suitably flattened or squared in order to accommodate properly the latter.

It will be seen that by loosening the bolts 100, the mountings are free to move longitudinally of the rack, which motion may be effected by turning the pinions 101 so as to slide the mount and associated devices along the rack to any desired position within the confines of the latter. Thus, the selvagers may be adjusted to any mesh size.

In the instant case, the trimming, welding, and forming instrumentalities have been simplified over those shown in my previous application in that the lightness of the wires composing the fabric to be acted upon permits of a lighter construction, and necessitates simpler mechanical movements being employed in carrying out the selvaging operation. In lieu of the cam shaft, whereby the selvagers of my copending application are actuated to perform their essential functions, electro-magnets have here been provided in conjunction with suitable timing means, whereby the selvagers are actuated at predetermined intervals necessary for their successful operation.

The first unit in the selvager battery is the welder, which, similar to my previously disclosed machine, consists of a pair of vertically aligned electrodes 105 and 105a between which the outermost warp wire is adapted to pass. These electrodes are mounted for limited oscillation upon pivoted bearings 106, 106a, respectively, formed in a standard 107, which is directly secured to the mounting 99. The lower electrode is caused to pivot about its axis 106a so that its working end moves upwardly toward the upper electrode by means of a lever 108 that is fastened to the shaft 106a so as to impart movement thereto. Solenoids 109 cause the lever 108, acting as their armature, to move down against the tension of a spring 110 when the solenoids are energized, which spring, when the solenoids are

de-energized, causes the electrodes to return to their position remote from each other.

This motion is imparted to the upper electrode in a reverse direction by means of a linkage comprising a downwardly depending yoke 111, which is affixed to the upper shaft 106, and an upwardly extending crank extension 112, which is affixed to the lower shaft 106a, which crank has a pin 113 within the limits of the yoke 111. This arrangement is such that rotary motion of the shaft 106a causes the crank 112 and its associated pin 113 to move through a circular path. This motion is imparted to the yoke 111, which, in turn, is effective to revolve the shaft 106 in a direction opposite to that in which the shaft 106a is turned.

As will be seen in Figures 10 and 11, the turning of these shafts is ineffective to move the electrodes directly, but rather, their movement is accomplished by the shafts' turning, respectively, lugs 114 and 114a, which lugs are adapted to impart the requisite motion to the electrodes through lugs 115-115a by means of compression springs 116. These springs are adapted to transmit the desired motion in a yielding manner so that any irregularities or variations in thickness in the material falling between the electrodes may be compensated for without causing injury to the parts. The springs 116, by maintaining a static pressure, also afford a quick compression movement on the welding points when the wires to be welded become hot and plastic. This spring pressure on the welding points is maintained until the weld has been cooled so as to make a substantial bond.

In the interests of affording more positive movement, the solenoids 109 are preferably of the double type, as is shown in Figure 10. Also, during the welding, when the electrodes are brought to bear upon the weft wires at their points of intersection with the outermost warp wires, there is a tendency for the hot wire to bend or wilt under its own weight. This tendency is circumvented by guide members 117 which are mounted stationarily upon the standard 107 so as closely to confine the picket ends from above and below. These guides 117 have the additional salutary effect of bringing the weft ends into approximate alignment in the plane of the fabric whereas they might otherwise have a tendency to flare outwardly therefrom in directions both above and below the fabric, due to the interweaving of the outermost warp wire therewith. It will be understood that the outermost warp wire, being under tension, has a tendency to deflect the unsupported weft ends, rather than to be itself deflected by them. This brings into consideration the matter of feeding the outermost warp wires in a manner whereby they are not unduly tensioned, and suitable means (not shown) are preferably provided for this purpose.

Leaving now the initial welders wherein the fabric is bonded together by the outermost warp wires' being welded to each picket wire as it goes by, the fabric goes on to the trimming and initial forming tool, which is shown in the intermediate position of Figures 10 and 11, and which is shown in varying degrees of enlargement and fragmentation in Figures 12, 13 and 14. Upon the mounting 99 of this tool, there is provided a standard 118 adjacent the top of which is a pair of pivot bearings 119-120, respectively.

The top of the standard 118 is provided with an outwardly extending portion 121 which over-

hangs the edge of the fabric being acted on. A stationary tool 123a is adjustably supported by the over-hanging portion 121 which, in the case of the trimmer, is sharpened at its lower edge for cooperation with a movable sharpened tool, about to be described, for trimming the picket ends. The movable member comprises a rotatable element 122, which is journaled in the bearing 120 of the standard 118. The sharpened tool 123 is rigidly affixed to the rotatable element for cooperation with the downwardly depending stationary tool carried by the overhanging part 121 of the standard. The movable tool 123 has motion imparted to it through the rotatable element 122 by means of a rearwardly extending arm 124, which is provided with fixtures 125 comprising the armatures of the pair of solenoids 126. When the latter are energized, the armature is pulled down by magnetic attraction, which causes the movable tool on the far side of the pivot 120 therefrom to move upwardly so as to trim the wires falling between the lower tool 123 and the upper tool 123a.

Mounted on the same standard and accommodated in the pivot bearing 119 is another arm 127 (see Figures 11 and 13), which carries a movable tool 128 at one extremity and at the other is secured to the armature 125 of the solenoids 126.

Arranged for cooperation with the tool 128 is a stationary backing-up tool 129 supported by the over-hanging portion 121 of the standard 118. The pivot 119 of the movable element of this forming tool is sufficiently high relative to the plane of the fabric, and the movable tool 128 is so positioned with respect thereto, that, when the former is rotated, the latter is caused to move not only upwardly into the plane of the fabric but forwardly as well, incident to its arcuate travel. The stationary cooperating tool 129 is, therefore, provided with a cut-away portion 130, which may best be seen in Figure 14, that enables the movable tool 128 to engage picket wires, and push them upwardly and inwardly in the direction of the web of the fabric. Thus, as the solenoids 126 are recurrently energized, the trimmer is induced to clip the ends of the picket wires so that they are all of uniform length; while, simultaneously, the former is acting on adjacent picket wires that have already been trimmed so as to dispose them in the position illustrated in Figure 14. In this latter connection it should be noticed that the bottom rear edge of the stationary tool 129 is slightly relieved as at 131 so that, incident to each picket's being bent upwardly and inwardly, the second bend is imparted for reasons to become apparent hereinafter.

The final selvaging tool is that which appears at the left-hand end of the assemblies illustrated in Figures 10 and 11, and which is shown individually in Figure 15. This comprises a standard 132 carried upon the mounting 99, which standard, upon the fabric approach side thereof, is provided with two extensions 133 and 134 adapted to project inwardly beyond the edges of the fabric above and below the latter, respectively. The upper extension 133 is provided at its inner end with a flanged roller 135, which is adapted to overlie and closely cooperate with a stationary guide 136 carried by the lower extension 134.

The clearance between the roller 135 and the stationary guide 136 affords a passage for the preformed fabric edges, and, as the latter pass therethrough, the upwardly and inwardly extending extremities of the pickets are turned

down sequentially by the roller into the position illustrated in Figure 18. They immediately pass on to the final welder which is mounted on the same standard 132, and which comprises a lower relatively stationary, rotary, electrode 137, and a movable upper electrode 138 of the pencil type, which is adapted for reciprocation in the vertical, so as to contact each picket at the point where the latter overlies the adjacent picket to which it becomes permanently welded thereby.

It will be observed that the roller 135 and co-operating guide 136 are relatively stationary, and the only element that is adapted to be moved in this particular assembly is the upper electrode 138. This motion is effected by mounting the electrode on an arm 139 that is pivoted in the standard 132 upon a bearing 140. The bearing 140 accommodates a downwardly depending arm 141, which constitutes an armature for a solenoid 142. This arm, in turn, is rigidly secured to an upwardly extending arm 143 that is arranged in alignment with the electrode arm 139, which is independently and freely mounted on the pivot 140. A compression spring 144 is interposed between adjacent surfaces of the arms 139 and 143. This provides a relief device similar to that discussed in connection with the initial welders for positively, though yieldingly, transmitting the motion afforded by energizing the solenoid 142 to the electrode, thus to compensate for any variations in thickness of the material passed therebetween, and to provide for further compression at the welding points when the wires to be welded become hot and plastic. The solenoid, upon being energized, draws its armature and connected arm 141 towards it, which, in turn, rotates the upstanding arm 143, as viewed in Figure 15, counter-clockwise, which tends to compress the spring 144 so as to urge the electrode arm 139 to move around its pivot at 140; and this, in turn, brings the electrode 138 into engagement with the material that is disposed against the relatively stationary, though rotatable, lower electrode 137. This operation welds and completes the selvaging of the fabric, which then appears as is shown in the left-hand end of the view of Figure 18, and as shown to size in Figure 19.

It will be understood that the solenoids for actuating the several selvaging instrumentalities are energized simultaneously through any suitable circuit maker-and-breaker, which may advantageously take the form of fiber cam discs acting on spring contacts. These same contacts may be utilized in the distribution and timing of the welding current to the several electrodes. In any event, a separate circuit interrupter is provided in the welding circuit to open circuit after sufficient current has passed to effect the welds so as to preclude burning the metal. This arrangement must be provided in addition to the local distributor and timer contacts operated, as by the fiber cams mentioned above, coordinately with the operating cycle of the machine, because were the machine to be stopped at a point in its cycle when the fiber cams have the welding circuit contacts in closed position, the wires being welded would be burned and destroyed before the welding current could be shut off. Hence, an auxiliary interrupter is employed that apportions just the right amount of welding current and no more, after which it breaks the welding circuit and precludes further welding, irrespective of the position of the electrodes and local contacts. This arrangement has been employed by me on the machine of my copending application. The

interrupter may be any one of the many devices now available on the commercial markets for performing similar functions, which because they are well known to the electrical art, has not been shown here.

As is described in my copending application hereinbefore identified, the selvaging units are mounted for collective movement in the direction of the fabric's travel during the interval in which they operate on the latter. This is to permit the selvagers to pace the fabric while acting thereon so as to preclude stopping the fabric for this purpose, which enables the delivery of the fabric to be continuous, uninterrupted and smooth. The means provided here for the attainment of this end are the same as shown and described in my copending application, but may be understood by reference to Figures 1, 2 and 3, hereof. As has already been described, the selvagers are mounted upon bases 97, which, in turn, are carried on a table 95. This table is disposed upon slide bearings 94 at each side of the machine, upon which it is adapted to be reciprocated through links and levers 193, a connecting rod or pitman 194, by an oscillating crank 195. The throw of this crank, and its operating period with respect to that of the machine, is just enough to reciprocate the table 95 and its associated selvagers an amount equal to one-half the distance between adjacent weft wires in the fabric. When moving with the fabric the selvagers are operating, and when moving in the return direction, the selvagers are inactive and free of the fabric. The throw of the crank 195 may be varied by moving the pitman bearing thereon relative to the axis of the power rockshaft 196 upon which the crank is mounted. Thus, any size mesh may be accommodated.

40

Fabric winding

There only remains for the fabric to be wound into a bundle, which is accomplished by a mechanism similar in most respects to that which I have already disclosed in my copending application hereinbefore referred to. It differs therefrom in the case of small mesh fabrics such as are under contemplation herein in the substitution of a relatively smooth surface friction drum for the dentelated roll, which was provided to cog with the interstices of larger fabrics such as were disclosed therein; and, also, in the addition of a simple, yet effective, instrumentality for coiling the fabric under uniform tension irrespective of the diameter of the bundle at any given time, thus compensating for the ever-varying factor of the diameter of the bundle.

The bundling machine is shown at the left-hand end of the view of Figure 1 and in Figures 16 and 17. It consists of a stationary housing 150 in which are journaled drums 151 and 152, and a bundling pole 153.

The fabric F is delivered from the machine from the lowermost of the fabric rolls 7 beneath the operator's platform O (see Figure 1) to the drum 151 beneath which it passes the lays around it for more than 180° in a reverse bend to the drum 152. It passes beneath and around this latter in another reverse bend and is attached to the underside of the bundle pole 153 about which it is wrapped. As will be seen in Figures 1 and 16 the drums 151 and 152 are positively driven by sprockets 154 and 155, respectively, at both ends of each roll which cooperate with chains 156 that are driven from opposite sides 70 of the machine proper by being associated with

driven sprockets 157 and 158, respectively; this latter sprocket appearing in Figure 1.

The bundling pole is driven, through a pulley 159 affixed to its shaft, and a belt 160, by a pulley 161 that is secured to the shaft of the roll 151, which is powered by the sprockets and chains above identified.

An idle friction roller 162 is disposed above the drum 152 upon which it bears by its own gravity in order to insure good frictional contact between the fabric, which passes between the roller and the drum, and the latter. This arrangement is sufficient to effect the positive pull-out of the fabric from the machine even when the bundle pole 153 is disconnected, as during the stripping 15 of a bundle therefrom.

It will be appreciated that at the commencement of the winding operation, the fabric is attached to the bundling pole, which, at such time, represents a coiling core of minimum diameter, and of minimum circumferential extent. This presupposes that the drive for the bundle pole must be of sufficient speed to wind the fabric tightly about the bundling pole at the outset, notwithstanding the fact that, as the bundle grows, the circumferential extent of the winding core increases, and more fabric at the same number of revolutions per minute of the bundling pole is taken up. Inasmuch as this operation commences with the size of the bundling pole and the speed of revolution thereof presenting ideal conditions for the lineal extent of fabric being delivered thereto, the changes incident to the growing of the bundle are such as to make these factors in excess of what is needed, necessitating that they be compensated for.

This compensation is effected by allowing for a certain amount of slippage to occur between the belt 160 and the pulleys 159 and 161, which constitute the main source of power for the bundling pole. However, the larger the bundle becomes, the greater is the mechanical advantage afforded the incoming fabric in resisting the rotation of the bundling pole, necessitating, in the interests of winding a tight bundle, that the drive to the bundling pole be made more forceful and more positive as the winding proceeds. This means that the allowable slippage must be kept under strict control and the frictional resistance thereto progressively increased in order that the fabric may be continuously wound without difficulty until a bundle of the proper size has been produced.

This problem has been solved by employing a belt tightener that is effective in gradually tightening the belt 160 automatically, synchronously, and proportionately to the growth of the roll of fabric upon the bundling pole 153. One such arrangement is illustrated in Figure 17 in which it will be observed that, upon the drive side 60 of the bundling pole, there is provided an up-standing member 163 from which extends an arm 164, which, at one of its ends, is pivoted as at 165 to the standard 163, and at the other of its ends is provided with suitable tension spring engaging means, such as a hook 166.

To the stationary housing of the bundling mechanism, at a point beneath one section of the belt 160, is pivoted an arm 167, to the outer end of which is secured an idle belt tensioning pulley 168. The raising and lowering of the arm tightens and loosens the belt 160.

Suitably pivoted to the standard 163, as upon a bearing 169, is a lever 170, which extends down and across the bundling pole adjacent one of its 75

ends. Upon the opposite side of the bundling mechanism is a lever 170a which corresponds to the lever 170, last described. Upon the outer end of each of the levers 170 and 170a is a shaft bearing 171 in which is journaled a roller shaft 172 by which an idle roller 173 is supported between the levers so as to over-lie and bear upon the bundling pole 153, or any fabric that may be rolled thereon.

As will be best seen in Figure 17, a cam 174 is associated with the lever 170 in such a manner as to have no movement relative thereto, but so as to be rotated about the pivotal axis of the lever as it is raised and lowered relative to the bundling pole.

The cam 174 is so arranged with respect to the pivoted arm 164 that any movement, which it is made to perform by the lever 170, is immediately transmitted thereto, for which purpose a cam follower roller 175 is provided on the arm 164 intermediate its ends.

A compression spring 176 is tensioned between the outer end 166 of the arm 164 and the outer end of the belt tightener arm 167 adjacent the pulley thereof.

A glance at Figure 17 will be sufficient to indicate the manner in which this device functions. When the winding operation is initiated, the roller 173 permits the levers 170-170a to assume their lowest position, at which point the associated cam 174 permits the pivoted arm 164 to assume its lowest position. As the bundle of fabric grows, the roll 173 is lifted a corresponding amount, which, in turn, raises the levers 170-170a so that the cam causes the pivoted arm 164 to move upwardly. Such movement increases the tension of the spring 176 which, in turn, urges the pulley 168 upward with greater force. This is responsible for increasing the tension on the belt 160 in a progressive manner so that the frictional drive of the belt 160 about the pulleys 159 and 161 becomes more and more positive. Finally, when the roll is at its maximum diameter, the roller 173, and associated levers, 40 will have caused the cam 174 to turn so that the high point in its periphery will have approached or attained a point beneath the arm 164 which will, in turn, have caused the belt-tightener pulley 168, through the spring 176, to exert its maximum 45 force upon the belt 160 in tensioning the same. 50

It should be noted that the contour of the cam 174 is such as to amplify the movements of the several levers in a way that the tension under which the compression spring 176 is at any 55 time working is approximately directly proportional to the thickness of the bundle (i. e., from the surface of the bundling pole to the surface of the bundle of fabric in the direction of a radius of the latter) at any given time.

The fabric

Attention is now called to Figures 14, 18, and 19, in which the fabric appears undergoing completion, and as completed. Reference has been 60 made hereinbefore to the second bend in the wire occasioned by the cut-away portion 131 at the bottom of the stationary forming tool 129 (see Figure 14). In the finished product, as viewed in Figure 18, this bend contributes to the final position of the wire portions B², but it will 65 be noticed that these portions are disposed at a greater angularity to the unformed portions of the wires P in the finished selvage than they are immediately after receiving the impression of the 70 tool face 131. This difference arises from the 75

fact that the roller 135 on the next succeeding selvaging unit not only rotates the formed ends of the pickets downwardly about the major axes of the wires P, but also causes them to undergo further bending in the direction initiated by the face 131 of the tool 129; this time, however, in a direction extending longitudinally of the fabric. Thus, in the finished selvage, the portions B² are disposed at an angularity to the body portions of the wires P that corresponds to that of the portions B¹, even though in the formative stage, as shown in Figure 14, these bends are not of equal magnitude. The result is a uniform, symmetrical selvage.

The selvaging sequence is schematically presented in Figure 18. The fabric F travels in the direction of the arrow T, and the pickets P, of approximate length only, are interwoven with the warp wires L and are presented to the initial welders in this condition. The initial welders join each picket to the outermost warp wires as at A, and the fabric passes on to the trimmer or cutter, where each picket is trimmed to final length as at C. The first former then imparts the initial bends, as shown in Figure 14, at B'. The fabric then passes the final former at R, where the preformed ends are turned down and spread out somewhat. The final weld is applied at D, and the fabric is completed.

Though the inventions are thought to be well illustrated by the descriptive matter hereinbefore set forth, such description, replete as it is with specification and detail, is not to be confounded with the scope of the inventions; for it is recognized that many modifications may be made, which will depart from the letter of this specification, but which clearly will partake of the spirit of these inventions, as is thought to be apprehended in and by the following claims.

I claim:

1. In a wire fabricating machine, means for interweaving warp wires and weft wires, means for bringing the weft wires' ends into line parallel to the warp wires, means for forming the ends of the interwoven weft wires so as to project them out of the plane of the interwoven body, and means for turning the formed portions of the weft wires substantially into the plane of the interwoven body by turning the formed portions about an axis of rotation coincident with the longitudinal axis of each picket.

2. In a wire fabricating machine, means for interweaving warp wires and weft wires, means for bringing the weft wires' ends into line parallel to the warp wires, means for forming the ends of the interwoven weft wires so as to project them out of the plane of the interwoven body a distance equal to or greater than the spacing between adjacent weft wires, and means for turning the formed portions of the weft wires toward the plane of the interwoven body, whereby the formed portions overlap adjacent weft wires.

3. In a wire fabricating machine, means for interweaving warp wires and weft wires, means for bringing the weft wires' ends into line parallel to the warp wires, means for forming the ends of the interwoven weft wires so as to project them out of the plane of the interwoven body a distance equal to or greater than the spacing between adjacent weft wires, means for turning the formed portions of the weft wires toward the plane of the interwoven body, whereby the formed portions overlap adjacent weft wires, and

means for securing the overlapped weft wires in this relationship.

4. In a wire fabricating machine, means for interweaving warp wires and weft wires to form fabric, means for bringing the weft wires' ends into line parallel to the warp wires, means for forming a portion of the weft wires projecting beyond the edge warp wire out of the plane of the fabric, and means rendered effective by the fabric's movement relative thereto for turning the formed weft wire portions about rotational axes that are substantially coincident with the longitudinal axes of the unformed portions of the weft wires, respectively.

15 5. In a wire fabricating machine, means for interweaving warp wires and weft wires to form fabric, means for selvaging said fabric including means for forming the ends of the weft wires into substantial perpendicularity to the plane of the fabric, and means for turning the so-formed ends over substantially into the fabric's plane, so as to dispose them longitudinally of the fabric.

6. In a wire fabricating machine, means for interweaving warp wires and weft wires to form fabric, means for advancing said fabric, means for selvaging said fabric including means for forming the ends of the weft wires into substantial perpendicularity to the plane of the fabric, and means rendered effective by the fabric's movement relative thereto for turning the so-formed ends over substantially into the fabric's plane.

35 7. In a wire fabricating machine, means for interweaving warp wires and weft wires to form fabric, means for selvaging said fabric including means for bringing the weft wire ends into line parallel to the warp wires, means for forming the weft wires adjacent their ends so that a length of each equal to or greater than the spacing between adjacent weft wires is deflected to a position substantially normal to the plane of the fabric, means for turning said formed ends about rotational axes that are coincident to the longitudinal axes of the unformed portions of the weft wires, respectively, into overlapping relation with adjacent weft wires, and means for securing the weft wire in this position.

40 8. In a wire fabricating machine, means for feeding warp wires, means for feeding weft wires across said warp wires to form pickets, means for advancing pickets in length approximating that required into interwoven relation with said warp wires to form fabric, means for bringing said pickets to the required length, means for forming the picket ends outwardly of the plane of the fabric, means for turning said ends back into substantial alignment with the plane of the fabric in a direction extending longitudinally of the latter, and means for securing the picket ends in this relationship.

45 9. In a wire fabricating machine, means for feeding warp wires, means for advancing picket lengths of weft wire into interwoven relation with the warp wires to form fabric, means for bringing said pickets to the same length in co-extensive relation to each other, means for imparting a double bend to the end of said pickets so as to deflect said ends out of the plane of the fabric, means for turning the deflected ends into overlapping relation, and means for welding the overlapped portions thereof in this position.

50 10. In a wire fabricating machine, means for feeding warp wires, means for advancing picket lengths of weft wire into interwoven relation with warp wires to form fabric, means for bring-

ing said pickets to the same length in coextensive relation to each other, means for bending the end of each picket into a position wherein it is approximately normal to the fabric's plane, and means for rolling the bent picket ends down in directions longitudinal of the fabric.

11. In a wire fabricating machine, means for feeding warp wires, means for advancing picket lengths of weft wire into interwoven relation with warp wires to form fabric, means for bringing said pickets to the same length in coextensive relation to each other, means for imparting a double bend to the end of each picket so as to deflect it out of the fabric's plane and inwardly toward the edge warp wires, and means for rolling the double-bent portions of the picket ends down in directions longitudinal of the fabric.

12. A metal fabricating loom comprising means for interweaving line bodies and cross bodies into a reticular unit, means acting on the ends of said cross bodies to bend them substantially normal to the plane of said unit, and other means for rotating said bent ends into approximately the plane of said unit.

13. A metal fabricating loom comprising means for interweaving line bodies and cross bodies into a reticular unit, means for advancing said unit past selvaging devices, said selvaging devices including means to trim the cross bodies to a uniform length, means to form the ends of said cross bodies, and means rendered effective by the movement of said unit relative thereto to dispose the formed portions of said cross bodies in engagement.

14. A metal fabricating loom comprising means for interweaving line bodies and cross bodies into a reticular unit, means for advancing said unit, means for trimming and forming the ends of said cross bodies during the movement thereof, means rendered effective by the movement of said unit relative thereto to dispose the formed portions of said cross bodies in engagement, and means for welding the engaging portions of said cross bodies together.

15. In a metal fabricating loom, means for interweaving line bodies and cross bodies into a reticular unit including a movable guide, means for feeding a length of the cross body stock through said guide for a predetermined distance, and means effective to indicate the failure of a cross body to pass through said guide such predetermined distance.

16. In a metal fabricating loom, means for interweaving line bodies and cross bodies into a reticular unit including a movable guide, means for feeding a length of the cross body stock through said guide for a predetermined distance, means associated with said movable guide recurrently to intersect the path of travel of said length of cross body stock therethrough, and means for actuating the last-named means to stop the loom upon failure of a length of cross body to pass through said guide for the predetermined distance.

17. A machine for weaving elongated metal stock including a device for advancing a length of stock from a supply thereof comprising a positively driven capstan, a loop guide for receiving stock from the capstan, feed rolls for drawing stock from said loop guide, and means for periodically interrupting the operation of the feed rolls.

18. A machine for weaving elongated metal stock including a movable guide, and a stationary guide associated therewith, in combination,

means for advancing a length of stock from a supply thereof to said guides comprising a positively driven capstan, a slack accumulator for receiving stock from said capstan, feed rolls for passing stock from said accumulator to said guides, means for intermittently operating the movable guide, and means coordinated with said last-named means for intermittently operating said feed rolls.

19. A machine for processing elongated metal stock including an enclosed stock guide comprised of a plurality of elongated guide elements, each of said elements having stock engaging faces arranged through approximately 90 degrees of arc thereon, one extremity of said stock engaging faces terminating in a lower bearing portion, the other extremity thereof terminating in an upper bearing portion, said elements being assembled together in a manner to dispose the upper bearing portion of each into engagement with the lower bearing portion of the other, whereby said stock engaging faces register to define a closed passageway through the assembled guide.

20. The method of making metal fabrics which includes interweaving elongated metal bodies to form fabric, selvaging said fabric by bending ends of the metal bodies projecting from the fabric's edge at an angle to the plane of the fabric, and then turning the bent ends into engagement with adjacent similarly bent and turned metal bodies.

21. The method of making metal fabrics which includes bringing weft strands and warp strands into interwoven relation, bending each weft strand near its end to project a portion thereof in length equal to or greater than the spacing between adjacent weft strands out of the plane of the fabric, turning said bent portions down to overlie and contact adjacent strands, and securing the contacting strands together.

22. The method of making metal fabrics which includes interweaving line wires and cross wires to form fabric, bending the cross wire ends at an angle to the fabric's plane, and rolling said ends longitudinally of the fabric to lay them down substantially in the plane thereof.

23. In a machine for forming a fabric composed of metal warp and weft wires, means for effecting a union at certain intersections of the warp and weft wires, means for selvaging the outer fringe formed as a result of thus interconnecting said warp and weft wires including means for bending the ends of the weft wires away from the plane of the fabric, means for turning the so-bent weft ends into the plane of the fabric, and means for autogenously integrating said ends with the fabric to thus form a selvage.

24. In a machine for forming a fabric composed of warp wires and weft wires, means for autogenously integrating each weft wire with the outermost warp wire in the region where it intersects said warp wire, means for severing each weft wire at a uniform distance from the outermost warp wire greater than the distance between adjacent weft wires, forming means for deflecting the end portions of the weft wires so their terminal portions extend inwardly and away from the plane of the fabric, means for turning the so-formed extremity of each weft wire into overlapped relation with an adjacent portion of the fabric, and means for autogenously integrating the said extremities with the fabric, thus forming a uniform selvage.

25. In a machine for forming a reticulated

body composed of warp wires and weft wires, means for autogenously integrating each picket wire in the region where it intersects an outer warp wire, means for severing each picket wire at a distance from the outermost warp wire greater than the distance between adjacent picket wires, means for deflecting the ends of the picket wires so their terminal portions point inwardly and away from the plane of the fabric, means for moving said terminal portions into the plane of the fabric and in cross relation with elemental portions thereof, and means autogenously integrating such cross related portions of the fabric.

26. In a machine for making wire fabric, means for interconnecting line wires with other wires at an angle thereto, means for welding portions of said other wires with certain of the line wires at their points of intersection there-

with, means for forming reentrant portions out of the plane of the fabric on the extremities of said other wires, means for positioning the latter in the plane of the fabric, and means for autogenously integrating the extremity of each said reentrant portion with the fabric thus produced.

27. In a machine for making wire fabric, means for interconnecting line wires with cross wires at an angle thereto, means for autogenously integrating outer portions of said cross wires with certain of the line wires at their points of intersection therewith, means for forming reentrant portions on the cross wires, means for bending the so-formed extremity of each cross wire into overlapping relation with an adjacent cross wire, and means for autogenously integrating the thus overlapped components of the fabric.
